UNITED STATES PATENT OFFICE.

JOHN JERZYK, OF RAINIER, OREGON.

STIRRUP.

1,130,607.

Specification of Letters Patent.

Patented Mar. 2, 1915.

Application filed March 17, 1914. Serial No. 825,301.

To all whom it may concern:

Be it known that I, JOHN JERZYK, a citizen of the United States, residing at Rainier, in the county of Columbia and State of Oregon, have invented new and useful Improvements in Stirrups, of which the following is a specification.

The invention relates to stirrups, and more particularly to the class of safety 10 stirrups.

The primary object of the invention is the provision of a stirrup wherein the foot of a horseback rider will be instantly freed therefrom should the horse stumble or fall, 15 thereby preventing the catching of the foot in the stirrup in such event, and thus obviating possible injury.

Another object of the invention is the provision of a stirrup wherein the same is 20 constructed to accommodate feet of different sizes to sustain the same in the stirrup when riding a horse under normal conditions.

A further object of the invention is the 25 provision of a stirrup which affords comfort as well as assured safety while in the act of riding, the stirrup being of novel form to render it durable and serviceable in every respect.

30 A still further object of the invention is the provision of a stirrup which is simple in construction, reliable and efficient in use, and inexpensive in manufacture.

With these and other objects in view, the 35 invention consists in the construction, combination and arrangement of parts as will be hereinafter fully described, illustrated in the accompanying drawing, and pointed out in the claim hereunto appended.

40 In the drawing: Figure 1 is a front elevation of a stirrup constructed in accordance with the invention. Fig. 2 is an edge elevation thereof. Fig. 3 is a fragmentary sectional view through the same. Fig. 4 is a sectional view on the line 4—4 of Fig. 1.

Similar reference characters indicate corresponding parts throughout the several views in the drawing.

Referring to the drawing in detail, the 50 stirrup comprises a frame 5 having the tread 6 and a loop or eye 7, the latter being adapted to receive the suspension strap for the stirrup. The side stretches of the

frame 5 are inwardly curved at 8 to reduce the width of the frame at the loop or eye 55 end thereof.

Journalled in the side stretches of the frame 5 are the stud ends 9 of crank arms 10 which telescope within guide tubes 11 integral with or fixed to bosses 12 formed on 60 an arched safety plate 13 which is disposed above the tread 6 of the frame 5 and is adapted to engage the foot of a rider when the said foot is resting upon the tread 6 of the frame 5 of the stirrup. Formed on the 65 tubes 11 are integral collars 14 in which and the said tubes are threaded set screws 15, the latter being adapted to engage the crank arms 10 to fasten the safety plate 13 in adjusted position and relatively spaced 70 with respect to the tread 6 of the frame of the stirrup, and in this manner the said stirrup will accommodate different sizes of feet. Formed at opposite ends of the safety plate 13 are stop ears 16 which are adapted 75 to contact with the side stretches of the frame 5 to limit the swinging movement of the stirrup plate in one direction.

Engaged with the crank arms 10 and the side stretches of the frame 5 are springs 17, 80 the coiled portions 18 of which embrace the stud ends 9 of the crank arms, and these springs serve to normally hold the safety plate 13 in position whereby the stop ears 16 contact with the frame of the stirrup, yet 85 on the rocking of the foot of a rider while it is engaged in the stirrup will swing the safety plate 13 in one direction, thus freeing the foot from the stirrup so that the rider will be liberated from the saddle when 90 riding a horse.

From the foregoing it is thought that the construction and manner of operation of the device will be clearly understood, and therefore a more extended explanation has been 95 omitted.

What is claimed is:—

A safety stirrup comprising a frame, levers pivotally connected to the sides of the frame and interiorly thereof, an arched safety plate disposed above the tread of the frame and having laterally extending stop ears at opposite ends thereof to abut the sides of the frame at the front only thereof, cylindrical bosses fixed to and rising from 105 the safety plate and adjustably receiving

therein the levers, set screws threaded in the bosses and engageable with the levers to permit the locking of the safety plate in adjusted position, and tension springs having portions thereof coiled about the pivots of the levers with their ends working against the frame and said levers respectively to normally hold the ears on the

safety plate in abutting relation to the sides of the frame.

In testimony whereof I affix my signature in presence of two witnesses.

JOHN JERZYK.
